Primary Examiner — Sandra Morris(74) Attorney, Agent, or Firm — Parks IP Law LLC; Collen A. Beard, Esq.(57) CLAIM

I claim the ornamental design for a bottle, as shown and described.

DESCRIPTION

FIG. 1 is a perspective view of a bottle in accordance with my new design;

FIG. 2 is a side view thereof, the other side is a mirror image; and,

FIG. 3 is a top view thereof.

The broken lines in the drawings are for illustrative purposes only and form no part of the claimed design.
